by the Secretary of War

Application March 26, 1946, Serial No. 657,143

5 Claims. (Cl. 250—33.65)

1

This invention relates generally to electrical apparatus, and particularly it relates to an R. F. antenna for aircraft installation which is horizontally polarized and has radiation patterns in horizontal planes which are free of deep nulls.

For numerous aircraft installations it is desirable to employ antennas having horizontal polarization and azimuth coverage in all directions. A type of military operation in which an antenna having these characteristics is needed is airborne jamming. Though sometimes there is a preference for good forward coverage, the jammer usually should transmit its signals in all directions. Moreover civilian aviation equipment such as communication apparatus and navigation aids might also require such an antenna since blind spots in their coverage would constitute a flying hazard.

In aircraft antenna installations a problem arises because radiating elements must of necessity be quite close to reflective surfaces of the plane and this can produce marked asymmetry in radiation patterns. This asymmetry is frequently unpredictable and may cause undesirable directivity or blind spots. Besides this problem, the antennas themselves have shortcomings. Many antennas having desirable characteristics such as small size, low input impedance, good structural strength, and simple construction, have horizontal radiation patterns with deep nulls. A dipole, as a simple example of an otherwise desirable horizontal radiator, has pronounced nulls in its horizontal pattern.

Prior art has already used a modified simple dipole, the two radiating halves of which are made to meet at same angle other than 180°. Such an antenna is sometimes called a V antenna, since its two radiating elements meet so as to form a letter V. V antennas have been installed in aircraft as single complete units. They have been installed either in front, above, below, or to one of the two sides of the fuselage. Installation on either side usually resulted in unpredictable asymmetry; installation above caused R. F. energy to move predominantly away from the ground; installation below interfered with landing; and installation in front favored forward radiation.

It is an object of this invention to provide a modified V dipole aircraft antenna installation having none of the disadvantages mentioned above. It is a further object of this invention to construct this antenna in such manner that it has horizontal polarization and that its radiation patterns in horizontal planes are relatively free of deep nulls.

2

Generally this invention comprises a V type of dipole with its two radiating elements physically set so far apart that the fuselage of the plane fits between them. In this installation these two radiating elements protrude from said fuselage and are supported with respect to said fuselage by supporting means physically connected to the fuselage.

Other objects, features and advantages of this invention will suggest themselves to those skilled in the art and will become apparent from the following description of the invention taken in connection with the single figure in the accompanying drawing in which the figure is an isometric view of a fragment of an aircraft fuselage showing the position of the various elements of the present invention with respect to the fuselage.

Referring now more particularly to the figure, the antenna itself may be considered as consisting of two radiating elements 1 and 2, each of which should have an effective electrical length near to one quarter wavelength corresponding to the midpoint of the operating frequency band. Because of the broad band features including in this embodiment, it is not always necessary that elements 1 and 2 be exactly a quarter wavelength and, therefore, they will be suitable for use over relatively large frequency bands. Fuselage fragment 3 has two openings 4 and 5 respectively which are large enough to permit elements 1 and 2 to protrude through the fuselage without being electrically grounded against the metallic skin of the aircraft. An insulating bushing may be inserted to fill the space between elements 1 and 2 and the perimeters of the respective openings 4 and 5 in the aircraft fuselage.

The elements 1 and 2 may be supported by brackets inside the fuselage and these brackets may be of any conventional type made in accordance with ordinary design principles. It is merely desirable that they have adequate strength to withstand air resistance during flight and that they should be adapted to electrically insulate elements 1 and 2 from the structure of the aircraft. Balun 6 is a conventional unbalanced to balance R. F. transformer and may be designed to be broad banded in accordance with conventional principles. Feed line 7 comes from a transmitter which is not shown and may be a low impedance cable of a conventional type. Lead-in lines 8 and 9 are similar cables which connect the output terminals of Balun 6 to outer conductive layers respectively forming conductive skin portions of elements 1 and 2. The

connection of lead-in line 8 to element 1 is made between inner conductor 10 of line 8 and a conventional dog-ear tab 11 which is joined to the conductive skin of element 1. Lines 8 and 9 have the ends of their outer conductors electrically connected to the conductive exterior skin of the aircraft at or near the point where elements 1 and 2 respectively emerge from openings 4 and 5 respectively.

Transformer tab 11 serves simply to avoid a marked discontinuity at this point where inner conductor 10 which is physically small joins said skin which is physically large. The corresponding connection between lead-in line 9 and element 2 is not shown in the drawing. Lead-in lines 8 and 9 should be kept as short as possible for the purpose of avoiding excessive attenuation losses. However, except for this consideration they are not of any critical length, but should be of equal length.

In operation, Balun 6 provides balanced R. F. energy for this antenna even though an unbalanced transmission line is used to feed power from the transmitter. If elements 1 and 2 were connected with their ends close together, and with each end connected to one of the output receptacles of Balun 6, they would comprise a dipole. Furthermore, if they were tilted back so as to form a V between them, they would then form a V type of dipole and this dipole would have the desired radiation characteristics. The use of lead-in lines 8 and 9 permits elements 1 and 2 to act in substantially the same manner while at the same time their ends are not close together but are, instead, separated by the fuselage of the aircraft. Inasmuch as lines 8 and 9 are of equal length and are fed with 180° out of phase through the action of Balun 6, elements 1 and 2 are fed 180° out of phase despite the distance between them. In general practice the two radiating elements forming V dipoles are made to meet each other at an angle of about 90°. It has been found that embodiments of this invention installed on Army B24D type aircraft worked well where the radiating elements were tilted back to form 50° angles with the axis of the fuselage. In these B24D installations these elements were also tilted downward, somewhat, so that they did not exactly lie in the same horizontal plane.

If elements 1 and 2 are made to be fairly thick with respect to their lengths, there are several desirable results: a good impedance match of each with its feed line; increased operating band width; and closer coupling to space. However, if the ratio of thickness to length exceeds 1 to 10, another problem arises. The incident traveling wave moving on the thick element is so attenuated in its travel along the length of the element, due to very close coupling to space, that little energy is left for the reflected wave and thus the levels of the two are markedly different. Therefore a new form of asymmetry is introduced and the main lobes of each element point off at angles other than 90° to the axes of these main elements. To overcome this it becomes necessary to modify the angle of tilt, of the element itself. Generally speaking, for an installation of the kind shown herein, the angle at which each element intersects lines parallel to the axis of the fuselage will be increased above said 50°, if elements 1 and 2 were to be made very thick.

Due to the complexity of the reflective areas offered by the surfaces of different aircraft trial and error methods are needed when this inven-

tion is first applied to a given aircraft. However these antennas have been installed in many types of military aircraft and have usually acted in a predictable and satisfactory manner. The antenna herein set forth will radiate energy with horizontal polarization and with such energy distribution that the radiation patterns in horizontal planes are free of deep nulls.

This antenna system can be looked upon as an array consisting of two modified antenna stubs, modified in that they are oblique, rather than perpendicular, to their respective reflecting planes. The axes of these modified stubs are coplanar and, if extended, meet at an angle of nearly 90°. The reflecting planes consist of parts of the fuselage; are substantially parallel to each other; and are separated from each other by the width of the aircraft. The two modified stubs extend from sides of said parallel reflecting planes which face away from each other and are fed R. F. energy 180° out of phase. The expression, antenna stub, as used herein, is intended to refer to an R. F. radiating element which is near to one quarter wavelength long and extends substantially perpendicularly from an associated reflecting plane.

It is also obvious that the installation is simple and lends itself to use in almost any conceivable type of aircraft.

It is obvious that elements 1 and 2 can be formed in any number of ways without departing from the spirit of the invention. They may be stream-lined but do not have to be; they may be either thick or thin; they may be composed of sheet metal, or solid metal, or of non-conductive core material with a metallic, or other conductive skin. It is also obvious that a Balun need not be employed at all, and that the two radiating elements can be fed directly from the conductors of a balanced pair.

As has been described above many departures from the embodiment precisely set forth herein can exist without departing from the spirit and scope of this invention.

Accordingly I claim all such departures as fall fairly within the spirit and scope of this invention as herein disclosed and as claimed in the appended claims.

What is claimed is:

1. An antenna array including two radiating elements of a dipole antenna and reflecting surfaces therefor, said elements being obliquely disposed with respect to said reflecting surfaces and mounted thereon, said reflecting surfaces being portions of opposite sides of a structure supporting said array, said reflecting surfaces being separated by an appreciable distance as measured in terms of the length of said elements, said elements extending from said sides of said supporting structure so as to point generally away from each other, said elements having axes which are substantially coplanar and which intersect said reflecting surfaces at angles at least as great as 45°, and feed means for exciting said elements with radio frequency energy 180° out of phase.

2. An antenna array as in claim 1 in which the points of intersection of said axes with said reflecting surfaces are so located on the opposite sides of said supporting structure that a line joining said points would form substantially equal angles with both of said surfaces.

3. An antenna array including two radiating elements of a dipole and reflecting surfaces therefore, said elements being disposed obliquely

with respect to said surfaces rather than perpendicularly, said surfaces comprising portions of opposite exterior surfaces of an airplane fuselage on which said array is mounted, said elements extending outward from said opposite sides of said fuselage so that they tilt backward toward the rear portion of said fuselage, said elements having axes which are substantially coplanar and which intersect said surfaces so that the angles measurable between said axes and said surfaces are at least as great as 45°, said elements being so located on the opposite sides of said fuselage that a line joining the points where their axes intersect said surfaces would form substantially equal angles with said surfaces, and feed means for exciting said elements with radio frequency energy 180° out of phase.

4. An antenna array including two longitudinal radiating elements of substantially equal size and reflecting surfaces therefor, said elements being disposed obliquely with respect to said reflecting surfaces rather than perpendicularly and mounted thereon, said reflecting surfaces being separated by an appreciable distance as measured in terms of the length of said elements, said elements extending from said reflecting surfaces so as to point away from each other, said elements having axes which are substantially coplanar and which meet their respective reflecting surfaces so obliquely that the angles measured between said axes and said respective reflecting surfaces are at least as great as 45°, and feed means for exciting said elements with radio frequency energy 180° out of phase.

5. A broad band antenna array having two reflecting surfaces, said reflecting surfaces comprising opposite sides of an airplane fuselage, a radiating element mounted obliquely on each of said reflecting surfaces, said radiating elements being thick in cross section relative to the lengths thereof, said radiating elements being separated from each other an appreciable distance as measured in terms of the wavelength of the desired operating frequency the axes of said radiating elements being coplanar and forming angles at least as great as 45° with said reflecting surfaces, and means to feed said radiating elements 180° out of phase with respect to each other.
